UNITED STATES PATENT OFFICE.

WILLIAM A. RANKIN, OF CHICAGO, ILLINOIS, ASSIGNOR TO EDISON ELECTRIC APPLIANCE COMPANY, INC., A CORPORATION OF NEW YORK.

ELECTRICALLY-HEATED DEVICE.

Application filed December 18, 1920, Serial No. 431,757. Renewed December 8, 1923.

To all whom it may concern:

Be it known that I, WILLIAM A. RANKIN, a citizen of the United States, residing at Chicago, in the county of Cook, State of Illinois, have invented certain new and useful Improvements in Electrically-Heated Devices, of which the following is a specification.

10 My invention relates to electrically heated devices such as ovens and the like and has for its object the improvement of such devices whereby their operation is rendered automatic.

15 In one aspect my invention comprises an improved electrically heated device such as an electrically heated oven in which the heat is automatically applied and cut off at predetermined times. My arrangement is such that the operator may set the apparatus in 20 advance and the operations will thereafter take place automatically when a predetermined time has arrived.

25 My invention includes timing means of an improved character having certain valuable characteristics prominent among which is the ease with which it may be started and stopped. In one form of my invention the arrangement is such that the timing device is automatically started when the timing device 30 is set and is stopped when the current is finally cut off from the oven.

35 In another aspect my invention comprises an improved arrangement which embodies both time and temperature control, so that the temperature is maintained approximately constant during the time the current is applied. The temperature control is effected by an improved thermostatic arrangement which enables the operator to conveniently determine the temperature which shall be reached in the oven. In other words, the operator knowing the temperature required, sets the apparatus for that temperature. Knowing also the time which 40 the cooking operation will require at that temperature and having in mind the time at which the operation should be completed, the operator sets the device so that the heat will be applied in time to insure the completion of the full cooking operation at the proper time. The operator may then leave the apparatus to take care of itself.

45 Other objects and purposes of my invention will appear in the course of the following specification in which I have disclosed

my invention embodied in concrete form for purposes of illustration.

50 In the accompanying drawings illustrating my invention Fig. 1 is a view of an electric range having an oven equipped with my improvement; Fig. 2 is a plan view of my improved thermostatic arrangement; Fig. 3 is a side view thereof looking in the direction of the arrow (Fig. 2); Fig. 4 is a 60 sectional view of the thermostatic switch mechanism; Fig. 5 shows the arrangement of the thermostatic element; Fig. 6 is a side view of the same and Fig. 7 is a diagram of the circuit connections.

65 Referring first to Fig. 7 it will be seen 70 that I have shown a number of heating units H, H', H'', H''' which, it will be understood, are located within the oven, which is preferably heat insulated (not shown) in a well understood manner. The electric circuit to these heating units is controlled by a timing device which serves as a clock and which I shall designate by the letter C. The circuit to the heating unit is also controlled by a thermostat designated by the letter T. The 75 thermostat T and the timing device C are in series so that the circuit must be completed through both the timing device and the thermostat before the circuit will be completed to the heating unit. The direct 80 control of the current to the heating devices is through an electromagnetic switch 10, the circuit of which is controlled by the timing device and the thermostat. The arrangement of the heating units in the circuit is 85 controlled by a plurality of switches 11 and 12.

90 The timing device which I have illustrated in a conventional way is an electrically driven device. The particular form of this 95 timing device forms no part of my present invention, since it is fully described and claimed in an application of Chester I. Hall, Serial No. 396,749, filed July 16, 1920. I have merely shown the essential elements of 100 such a device in order that its manner of functioning in my particular arrangement may be more clearly understood. As shown, I have illustrated an electric motor 13 of the eddy current type adapted to be connected to 105 the electric circuit to run at a substantially constant speed. This motor drives two discs which I have shown for purposes of illustration in the form of gear wheels 14 and 15 having mutilated portions 14' and 15' driven 110

by pinions 16 and 17. These gear wheels 14 and 15 are provided with openings 18 and 19 adapted to receive projections 20 and 21 mounted upon spring pressed switch members 22 and 23. The arrangement is such that when the gear wheels reach the proper position with reference to the projections 20 and 21, the projections will enter the openings and operate the contacts 24 and 25 associated with the switch member. These gear wheels 14 and 15 are preset in the proper position so that their openings will arrive at the point opposite the projections at the proper time by means of knurled wheels 26 and 27 provided with pointers 28 and 29 and a dial 30 cooperating with the pointers to indicate the position of the gear wheels. As illustrated, the gear wheel 15 is connected with the knurled wheel 26 by a sleeve 31 fitting over a shaft 32 to which the pointer 29 and knurled wheel 27 are connected. Springs 33 and 34 press gears 14 and 15 respectively to the right and into the positions shown in Fig. 7. It will be understood that by pressing on either of the knurled wheels 26 and 27, the gears will be moved out of mesh with the pinions on the motor shaft against the pressure of springs 33 or 34, and the gear wheels may then be turned freely so as to place the openings therein in proper positions as indicated by the pointers. Contacts 25 are open when the projection 21 is in its opening and contacts 24 are closed when projection 20 is in its opening.

It will be further understood that I have shown parts of this timing arrangement merely for purposes of illustration and have not attempted to show or describe the exact details of operation of the timing device.

The operation of the parts as thus far described will be as follows:—When the operator wishes to set the device for automatic operation he will turn the knurled wheel 26 until the pointer 28 indicates on the dial the time when the heating units are to be cut out of circuit, that is, when the heat is to be turned off from the oven. In doing so he presses on the knurled wheel 26 so as to release the gear 15 from its pinion and turns the knurled wheel, thereby moving the projection 21 out of the opening 19 in the gear 15 leaving it pressed against the face of the gear. This closes the contacts 25 and starts the motor 13, the circuit being from the positive side of the line through contacts 25, winding of the motor 13 and back to the negative side of the line. The operator also adjusts the pointer 29 to a position on the dial corresponding with the time when the current should be turned on. This action removes the projection 20 from its opening and opens the contacts 24. Assuming that the pointer 29 has been turned to four

o'clock on the dial and the pointer 28 to six o'clock on the dial: when four o'clock arrives the projection 20 will enter its opening and close the contacts 24 thereby energizing the electromagnetic switch or contactor 10 as follows—from the positive side of the line through the contacts 25, through contacts 24, thermostat T, winding of contactor 10 to the negative side of the line. This causes the contactor 10 to close and connect the heating units in circuit. The heat is now on in the oven. While the heat is on in the oven the thermostat, which is preferably located within the oven will maintain the temperature substantially constant by opening and closing the circuit at contactor 10. When the hour of six o'clock arrives the projection 21 will enter its opening thereby opening the contacts 25 to permanently deenergize the contactor 10 and cut off the heating units. The opening of the contacts 25 also stops the motor 13 leaving the projections 20 and 21 in their openings.

It will be noted that the gears 14 and 15 are mutilated so that when the projections enter the openings of the gears the smooth part of the gears will be opposite the pinions so that the gear can be stopped without interfering with the rotation of the motor.

Referring now to the construction of the thermostatic switch shown in Figures 2 to 6, the thermostatic member proper 35 (Figs. 5 and 6) consisting of an elongated strip or blade of thermostatic metal is mounted on a stationary support 36 within the oven as shown in dotted lines (Fig. 1). As shown, the thermostatic strip is tapered, its wide end having secured to it a bracket having two ears 37 through which the shaft 38 passes. The narrow end of the strip is provided with a slotted member 39 which receives a pin 40 which is adjustably secured in the support 36. On an increase in temperature the thermostatic strip will bend in the form of a bow, as shown in dotted lines in Fig. 5, thereby turning the shaft 38 to which the wide end of the element is screwed. Turning now to Figs. 2 to 4, it will be seen that a switch operating arm 41 is secured to the shaft 38 so that as the shaft turns it will turn the arm 41. This arm is provided with a sector 42 which is adapted to engage a switch lever 43 mounted upon an adjustable arm 44. This arm 44 has a hub 45 in which the shaft 38 turns so that the rotation of the shaft 38 does not affect arm 44. A quadrant 46 is provided to act as an outside support for the shaft 38 and the arms 41 and 44. This likewise provides a graduated scale 47 to act as an index for the two arms. The arm 41 is provided with a pointer 48 cooperating with this scale and the arm 44 is provided with a similar pointer 49 (Fig. 3) and a projection 50 which acts as an adjusting handle for the arm. By

means of this projection 50, therefor, the arm 44, which carries with it the switch mechanism, may be adjusted to the proper position as indicated on the scale 47 at which 5 the switch will be operated and the circuit of the contactor 10 opened. The quadrant is provided with a notched portion 51 which is engaged by a spring pressed pawl 52 on the arm 44 for holding the arm in various 10 positions.

The construction of the switch mechanism proper is shown in detail in Fig. 4 as consisting of an elongated block of insulating material 53 secured to the end of the arm 44. Pivotaly mounted upon this block is a switch lever 43 which operates the contacts controlling the circuit of contactor 10. As shown, the switch lever 43 which is not the contact lever, is provided at its outer end 15 with a roller 54 to be engaged by the sector 42. At its middle point the lever 43 is provided with a screw 55 engaging a ball 56 which in turn engages with a sliding member 57 having a pointed end. This pointed 20 end of member 57 engages a spring contact strip 58 which is normally in engagement with contact screw 59. When the switch lever 43 is engaged by the sector 42, the screw 55 forces the member 57 inward and 25 this in turn forces the contact spring 58 away from the contact screw 59 to break the circuit of the contactor 10. When the sector 42 is not in engagement with the roller 54 of switch 43 the contact spring 58 moves 30 into engagement with the contact screw 59 to close the circuit of contactor 10 and forces the switch member 43 is normally in a position 35 to be engaged and forced inward by the sector 42.

As thus constructed and arranged, the operation of my device is as follows: Assuming that the opearator wishes to have the current automatically turned on at four o'clock 45 so that the oven will be heated and that it is desired that the current be turned off at six o'clock, the operator will set the pointer 29 at the time indicated on the dial 30 at which it is desired that the current shall 50 be connected so that the circuit of the heating units shall be closed at four o'clock. This is done, as before stated, by pushing in on the knurled head 27 and turning the pointer to the proper position. Since the apparatus has been left in a position in which the projection 20 is in the opening 18 and the contacts 24 are closed, by turning the pointer the projection 20 rides on the face 55 of the gear 14 and opens the contacts 24. In like manner the pointer 28 is turned to six o'clock, the time when the circuit is to be opened, and the contacts 25 are therefore closed. This starts the timing device which in this case is an electric motor 13. The operator also sets the pointer on an arm 44 by

means of the handle 50 to the temperature at which the cooking operation is to take place; say, for instance, 400 degrees. Since the oven is then cold, the arm 41 and pointer 48 will be in the zero or lowermost position 70 (Fig. 2). When the temperature of the oven reaches substantially 400 degrees, the arm 41 will have advanced to a point where the sector 42 on the arm 41 engages the roller on the switch lever 43 and opens the circuit of the contactor 10, thereby cutting off the current. The temperature of the oven now starting to decrease, the arm 41 will move back and allow the switch 43 to again be closed. In this way the temperature within the oven will remain substantially constant. When the hour of six o'clock arrives the projection 21 will then enter its opening in gear 15 and open the circuit at the contacts 25, thereby cutting off the current in the oven and also stopping the timing device. It will be understood, of course, that the distribution of heat in the oven may be adjusted by adjusting the switches 11 and 12 in a well understood manner.

While I have described my invention as embodied in concrete form and as operating in a specific manner in accordance with the provisions of the patent statutes, it should be understood that I do not limit my invention thereto since various modifications thereof will suggest themselves to those skilled in the art without departing from the spirit of my invention the scope of which is set forth in the annexed claims.

What I claim as new and desire to secure by Letters Patent of the United States, is:—

1. An electrically heated oven or the like comprising a baking chamber, electric heating units therefor, thermostatic means for controlling the heating units, a normally inoperative timing device controlling the circuit through the heating units and thermostat, means for presetting the time at which the timing device will connect the heating units and thermostat in circuit and means whereby at a predetermined time after such presetting the heating units will be automatically disconnected and the timing device stopped.

2. An electrically heated oven or the like comprising a baking chamber, electric heating units therefor, thermostatic means for controlling the heating units, a normally inoperative timing device controlling the circuit through the heating units and thermostat; a manually controlled member for starting said timing device, means for presetting the time at which the timing device will connect the heating units and thermostat in circuit, and means whereby at a predetermined time after such presetting the member will be automatically operated to disconnect the heating units and stop the timing device.

3. The combination with an electrically heated oven or the like of a thermostatic device for controlling the same comprising a thermostat member located within the oven, a switch movable to various temperature positions outside of said oven and a member operated by said thermostat and cooperating with said switch in its various positions to operate the switch at the temperature at which the switch is set.
4. The combination with an electrically heated oven or the like of a thermostatic device for controlling the same comprising a contact device for controlling the heating units and mounted to rotate outside of said oven to various positions, an indicator cooperating with said switch to act as an index therefor and a member operated by the thermostat over substantially the same range as said contact device and cooperating with it in its various positions to automatically operate the contact.
5. The combination with an electrically heated oven or the like of a thermostatic device for controlling the same comprising a member mounted to rotate outside of said oven to various positions, a temperature indicator cooperating with said member to act as an index for presetting the same, a second member operated by the thermostatic element over substantially the same range as said first member, a contact device on one of said members and means on the other member for operating the contact device in the various presetting positions.
6. The combination with an electrically heated oven or the like of means for controlling the same comprising a thermostatic element within the oven, a switch rotatably mounted outside of the oven for adjustment to various positions and an actuating member for the switch operated by the thermostatic element concentrically with the switch.
7. The combination with an electrically heated oven or the like of means for controlling the same comprising a thermostatic element within the oven, and a contact device mounted outside of the oven for adjustment to various positions, an indicator therefor, a member operated by the thermostatic element and cooperating with said contact device to control the heating circuit of the oven and an indicator for said member whereby the temperature within the oven is indicated.
8. The combination with an electrically heated oven or the like of a thermostatic device for controlling the same comprising a thermostatic member located within the oven, a circuit controlling device including a switch and an operating member therefor, one of the members of said device being adjustable to various positions and the other cooperating therewith in its various positions to operate the switch at the temperature corresponding with the position occupied.

I witness whereof, I have hereunto set my hand this tenth day of December, 1920.

WILLIAM A. RANKIN.
